UNITED STATES PATENT OFFICE

2,687,800

CAN CARRIER

Kenneth A. Welmer, Marion, Ind., assignor to
Morris Paper Mills, Chicago, Ill., a corporation
of Illinois

Application July 19, 1952, Serial No. 299,811

1 Claim. (Cl. 206—65)

1 The present invention relates to improvements in a wrap-around type, paperboard carrier for a number of cylindrical cans or like articles of uniform size and shape, the improved carrier being distinguished by its simplicity of construction, its slight cost and the ease and speed with which it is manipulated into article encasing condition.

It is an object of the invention to provide an article carrier of the foregoing general description which is fabricated from a single, rectangular sheet of inexpensive paperboard stock die-cut and creased in a fashion to provide a double ply suspending handle and to provide spaced article accommodating and restraining openings in the side panels thereof which are engageable with opposite ends of the packaged cylindrical articles, the sheet being manually applied to the articles in a jiffy with the aid of a simple and inexpensive packaging fixture, and being quickly and safely sealed while in the fixture by means of a pressure sensitive cohesive or adhesive previously applied to overlapped bottom panels thereof. The improved carrier, and the package of which it is a part, eliminate need for expensive container set up and loading equipment, and the carrier is thus especially well suited for use by packers or distributors of a canned commodity at the cannery or point of distribution.

Another object of the invention is to provide an improved portable container package including a plurality of cylindrical sided cans, or equivalent containers or similar articles of uniform size and shape, arranged in a rectangular group or organization, together with an improved paperboard packaging unit wrapped around the group, this unit being characterized by an up-standing central suspending member of double ply construction and by top, side and bottom wall members which encase the rectangular container organization, the bottom wall of the wrapper unit being secured, in a substantially overlapped relation of a pair of bottom forming panels of unequal size, by means of a pressure sensitive agent striped in the overlapped zone.

Yet another object of the invention is to provide an improved flat, knocked-down, wrap-around packaging unit which is fabricated from a simple one-piece, rectangular paperboard blank die-cut, cut and creased to provide a handle opening and semi-circular article accommodating and restraining openings at the junction of its side wall panels with its top and bottom forming panels, and in which the bottom forming panels are of unequal length, each having a longitudinally extending stripe of pressure sensitive cohesive or adhesive applied to similarly facing, exposed surfaces thereof, the stripes being parallel and adapted to adhere firmly to one another when the knocked-down unit is applied to the articles

2 in the manner described in the preceding paragraph.

Generally, it is an object to provide an improved handle-type, wrap-around article carrier, and to provide an improved package of articles encased by such carrier, all as described above, in which the articles are positively restrained from endwise displacement from the packaging unit simply by nesting engagement of their upper and lower margins with certain article receiving apertures at the corners of the unit, the latter being devoid of lock flaps or like special provisions engaging the articles to prevent inadvertent displacement thereof.

The foregoing statements are indicative in a general way of the nature of the invention. Other and more specific objects will be apparent to those skilled in the art upon a full understanding of the construction and use of the package and component packaging unit.

A single embodiment of the invention is presented herein for purpose of illustration. It will be appreciated that the invention may be incorporated in other modified forms coming equally within the scope of the appended claim.

In the drawing:

Fig. 1 is a top plan view of a die-cut and creased rectangular paperboard blank employed in fabricating the improved wrap-around carrier or packaging unit;

Fig. 2 is a top plan view of the improved unit in a flat, knocked-down condition thereof prior to application to the packaged articles, illustrating the manner in which the parts of the blank of Fig. 1 are folded relative to one another, as well as showing the application of pressure sensitive stripe to bottom forming panels of the unit;

Fig. 3 is a transverse sectional view, partially broken away, illustrating conventionally a simple packaging fixture and indicating in dotted and solid lines the way the improved unit is manipulated to packaging relation to a plurality of the articles grouped with the unit in the fixture; and

Fig. 4 is a perspective view of the completed package, ready to be lifted and transported.

The paperboard blank 10 from which the improved carrier or package unit is formed is of perfectly rectangular outline, enabling its manufacture with maximum economy of stock. It is provided with a transverse crease line 11 somewhat to one side of its vertical center line, and with a pair of creases 12 paralleling and equidistant from crease 11 on either side of the latter. These creases define a pair of like, transversely elongated handle forming panels 13, hinged to one another at crease 11.

Top wall forming panels 14 on either side of

the pair of handle panels 13 have their margins at the respective creases 12 and at the respective parallel series of transversely aligned creases 15. Further sets or series of transversely aligned creases 16, parallel to creases 12 and 15, coact with the latter in defining side wall forming panels 17, while a pair of terminal bottom forming panels 18, 19, of smaller and greater width, respectively, lie outwardly of the two respective sets of creases 16.

Circular can accommodating and retaining apertures 20 are formed at transversely spaced points along the respective sets of creases 16, the centers of the apertures being on the line of the creases and being spaced from one another a distance approximately equal to the diameter of the cans C (Figs. 3 and 4) which are to be encased by the packaging unit. Handle panels 13 are each provided with a hand hole 21, one side of which coincides with the crease line 12 of the panel. One of the hand holes is also provided with a protective flap 22, hinged to the panel 13 by a medial, transversely extending crease 23.

The packaging unit which is ultimately formed from blank 10 is shown in Fig. 2, being generally designated by the reference numeral 24. In completing the blank to this flat, knock-down form, ready for use, the blank is simply folded upon itself about the medial handle crease 11, and the two handle panels 13 are secured to one another, as by the use of a suitable adhesive, or by staples 25, or both. Panels 13, so secured, constitute a relatively rigid gripping and suspending member 26 of two-ply construction. The shorter multi-panel section 14, 17, 18 to one side of member 26 overlies the similar but more elongated multi-panel section 14, 17, 19, the can accommodating apertures 20 being in register. Bottom panel 19 longitudinally overextends bottom panel 18 substantially, as illustrated in Fig. 2.

With the packaging unit in this relatively flat, knocked-down condition, the same is passed through a coating apparatus, by which continuous parallel stripes of a suitable pressure sensitive cohesive or adhesive are applied to the upwardly facing surfaces of panels 18, 19, as indicated by stippling in Fig. 2. A cohesive, if used has the advantage that it adheres firmly to a similar coating on another surface but is non-adherent to an uncoated surface. Thus sticking of stacked units 24 or offsetting of adhesive do not constitute a problem.

It is intended that the improved packaging unit 24 be supplied in the flat, knock-down shown in Fig. 2 for use at a cannery, a brewery, etc., or at a distributing establishment through which the commodity in question is handled. Completion of the package will be performed at such establishment by its own personnel. A very simple packaging fixture, such as is illustrated in Fig. 3 and is generally designated 27, may be employed for the purpose.

This is a box-like device, comprising a special bottom 28; side walls 29 and end walls 30 secured in fixed rectangular relation, the bottom being provided with a depending center board 31 which is longitudinally and internally grooved at 32 to provide a slot whose depth approximates the height of handle 26 of packaging unit 24. The width of bottom wall 28 is slightly greater than the combined widths of the two top panels 14 and its length approximates the transverse dimension of unit 24. Its side walls 29 may be

coextensive in height with side wall panels 17 of the unit and its end walls may be of slightly less height, in order to facilitate removal of the completed package from fixture 27.

5 In assembling the package, the handle of the unit is introduced into fixture slot 32, whereupon downward force is exerted on the adjoining panels. This causes top panels 14 to swing downwardly about handle creases 12 into flatwise engagement with the fixture bottom 28. Side wall panels 17 similarly flex upwardly about creases 15 and assume upstanding, side by side engagement with fixture side walls 29.

With packaging unit 24 in this position, a group 15 of cans C is placed therein, as illustrated in Fig. 3, the rounded ends of the can being received in the semi-circular apertures 20 at the side and bottom corners of the unit. Upstanding bottom panels 18, 19 are then folded inwardly and downwardly about creases 16, in the order named, bringing the pressure sensitive adhesive stripes of those members into contact with one another, whereupon pressure is applied to the zone of the stripes. This results in a firm and displacement 20 resisting securing of the adhesive, completing the package. The latter may be removed from fixture 27 simply by upending the latter, or by lifting the package at the exposed ends thereof which project above the end walls 30 of the fixture. Appropriate pedal operated ejector means 25 may also be provided, if desired.

The package is simple, compact in the extreme and very inexpensive to assemble right at a cannery or brewery. It requires no complicated carrier erecting or loading apparatus, as is the case with fully assembled article carriers or cartons, even of the collapsible type. No preparatory operations of any sort, such as gluing or folding, are required prior to loading. The units 24 are supplied to the purchaser, ready for immediate use, in the knocked-down condition of Fig. 2. They obviously occupy a minimum space in shipment and in storage prior to use.

I claim:

45 A paperboard article packaging unit adapted to be assembled in box-like outline to encase a plurality of cans or similar identical objects arranged in row formation, said unit comprising a pair of generally similar rectangular paperboard sections integrally connected to one another by means including a crease at corresponding margins thereof and disposed flatwise in face to face contact, said sections each comprising rectangular handle, side wall and bottom panels integrally connected by parallel creases in the order named, the respective handle and side wall panels having corresponding creased margins thereof in register with one another, said bottom panels being of unequal width in the direction from creases 50 hinging the same to the respective side wall panels, and a stripe of pressure sensitive adhesive coated parallel to said creases across surfaces of each of said bottom panels which are exposed in the same direction, said adhesive being in a dry condition and non-adherent to a similar, uncoated surface, and means securing said sections in said flatwise contact at said handle panels.
